UNITED STATES PATENT OFFICE.

JOHN P. NEFF, OF EAST ORANGE, NEW JERSEY, ASSIGNOR, BY MESNE ASSIGNMENTS,
TO AMERICAN ARCH COMPANY, OF NEW YORK, N. Y., A CORPORATION OF DELA-
WARE.

LOCOMOTIVE-BOILER FURNACE.

1,138,055.

Specification of Letters Patent.

Patented May 4, 1915.

Application filed July 24, 1913. Serial No. 780,880.

To all whom it may concern:

Be it known that I, JOHN P. NEFF, a citizen of the United States, and a resident of East Orange, Essex county, State of New Jersey, have invented certain new and useful Improvements in Locomotive-Boiler Furnaces, of which the following is a specification.

My invention relates to improvements in locomotive boiler furnaces, and has particular reference to improvements in refractory baffle walls or arches for use in the fire boxes of locomotive boilers.

The object of my invention is to reduce the installation and maintenance cost of arches or baffle walls in locomotive boiler fireboxes; to provide an arch of such form and construction that it can be erected in position and repaired with little expenditure of time and labor, and to provide an arch which shall be constructed of a single pattern or form of brick and which shall be securely held and maintained in position.

A further object of my invention is to provide a locomotive arch composed of a plurality of transverse rows of identical bricks in which the bricks of each row shall mutually retain each other in position.

A further object of my invention is to provide a locomotive arch supported upon tubes and in which each brick shall have three points of support, all of the bricks being identical in form.

A further object of my invention is to provide a locomotive arch which shall be composed of a plurality of overlapping bricks which all lie substantially in a single plane and in which each brick shall rest upon two points at one end and one point at its other end.

A further object of my invention is to securely position an arch body supported upon tubes and composed of a plurality of bricks, in a firebox, by means of side bricks which are rigidly positioned between the side sheets and the adjacent tubes.

A further object of my invention is to provide in a locomotive firebox a refractory arch proper, composed of a plurality of individual bricks resting upon the tubes and free to change its dimensions relatively to its supports, and held in position by side bricks which extend between and are sup-

ported by the side sheets and the adjacent tubes.

My invention resides in an arch for use in a locomotive firebox, equipped with longitudinally extending water circulating tubes, which are not necessarily parallel, the arch being constructed of a plurality of refractory bricks, the main body of the arch resting upon the tubes and being held securely in position by side bricks which rest against the side sheets of the firebox and upon the adjacent tubes.

My invention consists in a locomotive boiler firebox provided with a refractory arch, the arch being preferably supported upon water-circulating tubes and composed of a plurality of substantially identical bricks mutually interlocked in position between the side sheets of the firebox and upon the arch tubes, and each brick resting upon three points of support.

My invention further consists in a locomotive firebox refractory arch composed of transverse rows of bricks extending from side sheet to side sheet and supported upon longitudinally extending water-circulating tubes, the individual bricks being identical in form, the end bricks of the rows being arranged between the side sheets and the adjacent tubes, and being adapted to retain the intermediate bricks in position upon the tubes.

My invention also consists in a locomotive boiler firebox having a plurality of longitudinally arranged water-circulating tubes, which are not necessarily parallel, in combination with a refractory arch supported by said tubes, the arch proper resting upon the tubes and being capable of changing its dimensions relatively to its supports without undue strains and being held in position by side bricks wedgingly interposed between the side sheets and the adjacent tubes.

My invention also consists in a locomotive boiler firebox arch made up of substantially identical bricks each having a V-shaped projection on one end and a complementary V-socket at the opposite end, the socketed ends being of half thickness and thereby providing the brick with a tube-receiving groove or socket and adapting the bricks when alternate bricks are reversed to overlap and to mutually retain each other in position.

- My invention also consists in a refractory arch brick, substantially rectangular in form, having a V-projection at one end, and a complementary V-socket at the other end, 5 the socketed end being cut away on one side to substantially half the thickness of the brick, and the brick being tapered in thickness from the socketed end to the opposite end.
- 10 My invention also consists in the various features of construction, and combinations and relations of parts, whereby a firebox arch can be provided which fulfills the above and other objects and which is built of one 15 pattern brick so formed that the individual bricks are each provided with three points of support and the adjacent bricks in transverse rows mutually interlock with each other.
- 20 My invention will be more readily understood by reference to the accompanying drawings, forming a part of this specification, and in which:

Figure 1 is a central vertical longitudinal 25 section of a locomotive firebox provided with an arch made in accordance with my invention; Fig. 2 is a transverse section of the firebox taken on the line 2—2 of Fig. 1; Fig. 3 is a detail transverse section of the arch on 30 the line 3—3 of Fig. 1; and Fig. 4 is an enlarged perspective view of one of the arch bricks.

In building arches for locomotive boiler fireboxes, it is a common practice to install 35 longitudinally extending water circulating tubes in the firebox upon which to support or carry a refractory baffle wall or arch and these arch tubes, while they are supposed to be arranged in parallel relation, are sel- 40 dom exactly parallel for the reason that the location of their ends depends to some extent on the position of adjacent stay bolts and rivets. Furthermore, by reason of the fact that these tubes are usually bent or curved 45 between their ends, it is almost an impos- 50 sibility to secure them in position exactly parallel with each other. For this reason it is desirable that the bricks of which the arch is formed shall be capable of being posi- 55 tioned upon the tubes in such a manner that they will be securely held in position regard- 60 less of the exact spacing of the tubes or of the exact distance of the side tubes from the side sheets. The form of brick which I have 65 devised, and with which I build my im- 70 proved arch, allows of considerable latitude in the positions and spacings of the tubes both as related to other tubes and as related 75 to the side sheets of the firebox without mili- 80 tating to any extent against the efficiency of the arch or against the security with which the arch as a whole and the bricks individ- 85 ually are held in position against the severe vibration and jarring to which arches in 90 locomotive boilers are subjected in use.

A locomotive firebox A, as illustrated in the drawings, is made up of a flue sheet a^1 , at its forward end, a rear sheet a^2 at its rear end, side sheets a^3 and a crown sheet a^4 . Flues a^5 lead forward from the flue sheet 70 and the rear sheet is provided with a fuel door or opening a^6 and the box is provided with a grate a^7 . The function of a front arch, as installed in a locomotive firebox, is to prevent the direct flow of the gases of 75 combustion from the fuel bed to the flues and cause them to flow backward and forward through the firebox in contact with the interior surface thereof and also cause them to be thoroughly intermingled and inter- 80 mixed and thereby result in the highest degree of economy and efficiency.

While my invention may well be employed for the construction and maintenance of arches other than front arches, I have illustrated my invention as particularly adapted to the building of front arches, but it should be understood that my invention is not limited to this particular position and use of an arch in a locomotive boiler furnace. 85

The firebox shown is equipped with a group of three water-circulating tubes a^8 which lie in substantially a single plane and which tubes extend from the lower part of the flue sheet upwardly and rearwardly 90 through the firebox to the upper part of the rear sheet. They serve the primary purpose of increasing the circulation of water in the boiler and thus adding to the efficiency of the firebox. I make use of these tubes as 100 supporting means for the arch B. The arch, as illustrated, consists of the arch body proper C, which is laterally coextensive with the group of arch tubes and which rests upon the tubes, and side portions D which extend 105 between the side sheets and the adjacent arch tubes. I build my arch of a number of 110 bricks b^1 which are identical in shape, form and size, being adapted to be formed or molded in a single mold or in identical 115 molds. My object in this is to reduce the cost of the production of the bricks and to reduce the cost of maintaining the arches on account of the reduction in the number of 120 bricks which it is necessary to carry at different points along the roadway for the re- 125 pairing of arches. These bricks b^1 are pecu- 130 liar in form. They are substantially rectangular and are tapered in thickness from end to end, the end b^2 being the thicker end, and the end b^3 the thinner end.

Half the thickness of the brick is cut away at the thick end of the brick, forming a groove or channel b^4 , and a projecting half-thickness ledge or flange b^5 , and this 125 end of the brick is also provided with a relatively large V-shaped groove or notch b^6 providing the brick with two spaced projections b^7 upon one face or side. I provide the opposite end of the brick with a central 130

V-shaped projection b^8 which may be described as complementary to the V-shaped notch or opening b^6 provided in the opposite end, and, furthermore, I lighten the brick 5 by providing each face with a shallow depression b^9 occupying substantially the whole of the body portion of the brick. The bricks as thus formed are adapted to be placed between the side sheets and the adjacent tube, as clearly shown in the drawings, the tube being received in the groove or notch b^4 of the thick end of the brick and the V-shaped projection b^8 being adapted to contact with the side sheet of the firebox. 10 The brick when thus positioned is supported upon two projections b^7 at one end and upon the V-point b^8 at the other end, being thus supported upon three points the brick is securely and rigidly supported in position, 15 even in conditions where the side sheet of the firebox is not parallel with the adjacent tube. The main body C of the arch is composed of several transverse rows of the bricks, each row being composed of two of 20 the bricks. These bricks are reversed in position, their thick ends being arranged upon the center tube and in overlapped position, whereby the body of the arch at this point is substantially one-brick thick, and the V-shaped ends of the bricks are adapted to 25 rest upon the outer tubes and to be received in the notches b^6 of the side bricks and thereby complete the arch. Each of the 30 bricks of the body of the arch thus rests upon three points of support and the bricks are thus held solidly and firmly in position even when the tubes upon which they rest do not lie in a single plane. The arch as thus built is substantially imperforate, 35 except for the small openings c^1 which are formed between the overlapped ends of the 40 bricks forming the main body of the arch, and as these openings occur directly above the center tube this tube serves practically 45 to close these openings. The main body of the arch as thus formed rests upon the upper surfaces of the tubes and is not bound in 50 position thereby, consequently the tubes do not necessarily have to be arranged exactly parallel with each other, but are free to be 55 positioned in the firebox in conformity with the individual necessities. For instance, it sometimes occurs that stay bolts or rivets are arranged in such positions that it is impossible 60 to place the arch tubes exactly parallel with each other. Furthermore, the bricks of which the side portions of the arch are composed, can individually adjust themselves to their positions to be firmly supported between the side sheet and the adjacent tubes. The main body of the arch is, however, maintained in position and prevented from changing its position sufficiently to permit the destruction of the 65 arch by the inner ends of the side bricks which span and receive the V-shaped ends of the center bricks. The arch as a whole consists of a plurality of transverse rows of bricks which extend from side sheet to side sheet, the individual bricks of each 70 row mutually interlocking with each other and maintaining each other in position. 75 In building front arches in conformity with my invention, I first arrange a transverse row of the bricks upon the lower ends of the tubes extending from side sheet to side sheet, the intermediate bricks being substantially horizontal and resting upon the upper surfaces of the tubes, the end bricks being arranged as described in upwardly and outwardly inclined positions 80 and retained in position between the side sheet and the tube. These end bricks, as described, interlock with the intermediate bricks and retain them in position. In 85 some instances I place spacing bricks F between this first transverse row of bricks and the flue sheet to hold the lower end of the arch out of engagement with the flue sheet. Having placed the first transverse row of 90 bricks in position, I place a second transverse row of the bricks, similar to the first row, and resting against and maintained in position by the first row on the tubes. In 95 some instances these two transverse rows provide an arch of sufficient length to produce the results desired, but usually the arch consists of further transverse rows of 100 bricks and for the most economical and best results is usually extended rearwardly to substantially the middle of the firebox. 105 An arch constructed in accordance with my invention is thicker at the center portion of the arch than along the side portions. This is advantageous, as the center portion of the arch is necessarily exposed to the most severe destructive temperatures and abrasive effects. Furthermore, an arch constructed 110 in accordance with my invention provides relatively small V-shaped openings between the outer edges of the arch and the side sheets through which portions of the rising gases of combustion may pass in contact with the side sheets and thereby add to the efficiency of the firebox by making use of substantially the whole of the interior surface 115 of the firebox for the purpose of transmitting the heat from the gases of combustion to the water in the boiler. The recesses or depressions b^9 in the brick provide an arch which is more or less rough upon its surface and this roughened surface serves to cause the retarding of portions of the rising gases and of the fuel particles carried thereby and serves to thoroughly intermingle and intermix the gases resulting in the complete oxidation of the fuel. An arch constructed of individual bricks in the manner described 120 lends itself readily to the convenient repair of the firebox, for the reason that when it is 125 130

necessary to get at the side sheets or flue sheet for repairs the individual bricks of the arch can readily be removed without destroying or taking down the whole arch 5 to give this access.

As many modifications of my invention will readily suggest themselves to one skilled in the art, I do not limit or confine my invention to the specific structures herein 10 shown and described.

I claim:-

1. A locomotive boiler firebox having longitudinally extending inclined arch-supporting tubes therein, in combination with a 15 refractory front arch supported by said tubes and comprising a plurality of transverse rows of identical bricks arranged end to end, each brick having a V-shaped projection on one end and a complementary V-shaped recess at the opposite end, the projections and 20 recesses of adjacent bricks being adapted to interfit.

2. A locomotive boiler firebox containing a group of longitudinally extending arch 25 supporting tubes, in combination with a refractory arch proper laterally coextensive with said group and comprising rows of bricks overlapping at their inner ends, the outer ends thereof having V-shaped projections, and similar side bricks resting at their 30 inner ends upon the side tubes of the group and contacting at their outer ends with the side sheets of the firebox, the inner ends of said side bricks spanning said V-shaped projections and limiting the movement of the arch 35 proper on the tubes.

3. A locomotive boiler firebox containing a group of longitudinally extending arch-supporting tubes, in combination with a 40 refractory arch extending from side sheet to side sheet and supported by said tubes, said arch having a middle portion transversely coextensive with said group of tubes composed of bricks identical in form, each there- 45 of being cut away at one end to substantially half the thickness of the brick, adjacent bricks being adapted to be reversed in position with their cut-away portions overlapped, the outer ends of said bricks having 50 V-shaped projections which rest upon the outer tubes of the group, side bricks resting on the outer tubes of the group and leaning against the side sheet, the inner ends of said side bricks having projections which span 55 the V-shaped points of the middle bricks and adapted to limit the movement of the middle portion of the arch upon said tubes.

4. A locomotive boiler firebox having a group of longitudinally extending arch-sup- 60 porting tubes therein, in combination with a refractory arch extending from side sheet to side sheet and comprising a middle portion transversely coextensive with said group of tubes, and side portions extending be- 65 tween the sides of said group and the side

sheets of the firebox, said middle portion of the arch having serrated edges resting on the side tubes of the group, the side portions of the arch having similar serrated outer edges resting against the side sheets and 70 inner edges provided with complementary recesses receiving the serrations of the center portion and serving to limit the movement of the center portion of the arch on the tubes.

5. A locomotive boiler firebox having three 75 transversely spaced longitudinally extending arch-supporting tubes therein, a refractory arch supported by said tubes and comprising a center portion coextensive with said group, and side portions extending between 80 the outer tubes and the side sheets of the firebox, said center portion being composed of a plurality of transverse rows of two bricks each, each brick extending between 85 and supported by two tubes, the meeting ends of the bricks being cut away to half thickness and arranged in overlapping position, the outer ends of the bricks being provided with V-shaped projections resting upon the outer tubes, the side portions of 90 the arch comprising similar bricks having their V-shaped projections in contact with the side sheets of the firebox and their half-thickness ends arranged to span the side tubes 95 of the group, said half-thickness ends being provided with V-shaped recesses to receive the adjacent V-shaped points of the middle bricks and serving to limit the movement of the middle portion of the arch upon the tubes.

6. A locomotive boiler firebox having three transversely spaced, longitudinally extending, arch-supporting tubes, in combination with a refractory arch therein extending from side sheet to side sheet and composed of 105 a plurality of identical bricks, each brick having a V-shaped projection on one end, a complementary V-notch on the other end, said notched end being cut away on one side to substantially half the thickness of the 110 brick providing spaced projections, each said brick being thereby provided with three points of contact, the outer bricks being arranged with their V-shaped projections extending outwardly and resting on the outer 115 tubes, and the outer bricks being arranged with their V-shaped projections against the side sheets of the firebox, and their notched ends resting on the side tubes and receiving the projections of the middle bricks between 120 their spaced projections and serving to limit the transverse and longitudinal movement of the middle portion of the arch upon the said tubes.

7. A refractory brick for use with other 125 similar bricks, in a locomotive boiler arch, said brick having a V-shaped recess in one end providing the brick with two spaced supporting projections and a central V-shaped supporting projection at the oppo- 130

site end complementary to the V-shaped recess.

8. A locomotive boiler firebox containing a group of longitudinally extending water-circulating tubes, in combination with a refractory arch supported by the tubes and composed of a plurality of identical bricks having two symmetrically disposed half-thickness projections at one end adapted to 5 cooperate with the like end of another brick, and a single complementary projection at the other end adapted to cooperate with the opposite end of a similar brick and whereby each brick is provided with three points of 10 support, and the arch is shiftable transversely of the tubes.

9. A locomotive boiler firebox containing a group of longitudinally extending arch supporting tubes, in combination with an 20 arch body transversely co-extensive with the group of tubes and resting upon the upper surfaces only thereof, said arch body being composed of a plurality of identical bricks having symmetrically disposed substantially 25 half-thickness projections at one end adapted to cooperate with the similar end of another brick to form a single thickness arch, and providing the brick with a tube-receiving

groove adapted to engage a tube when the brick is positioned between a side sheet and the adjacent tube, each said brick having a central projection at its opposite end adapted to be received between the projections on other bricks, as and for the purpose specified.

10. A locomotive boiler firebox containing a group of longitudinally extending water-circulating tubes, in combination with a refractory arch body supported on said tubes and laterally co-extensive therewith, said arch body composed of a plurality of individual bricks arranged in a single plane, each thereof being of a length to span and be supported by adjacent tubes, and provided upon one end with spaced projections and upon the other end with a projection 45 complementary thereto and all of said projections being adapted to extend beyond the center lines of the supporting tubes.

In testimony whereof, I have hereunto set my hand, this 15th day of July, 1913, in the presence of two subscribing witnesses.

JOHN P. NEFF.
